(57) **CLAIM**

The ornamental design for a ceiling fan light kit as shown and described.

DESCRIPTION

FIG. 1 is a front top perspective view of a ceiling fan light kit showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a front bottom perspective view thereof; and,
FIG. 9 is a front bottom perspective view in accordance with my design, shown in its environment thereof.
The broken lines illustrate portions of the ceiling fan light kit that form no part of the claimed design.
